United States Patent Office

Des. 184,363
Patented Feb. 3, 1959

184,363

CHILD'S PURSE

Charlotte B. Mahnken, St. Louis, Mo.

Application September 18, 1958, Serial No. 52,687

Term of patent 3½ years

(Cl. D87—3)

FIG. 1

FIG. 2

FIG. 3

Figure 1 is a front elevation, Figure 2 is a side view and Figure 3 is a rear elevation of the child's purse, showing my new design.

I claim:

The ornamental design for a child's purse, as shown.
